(57) CLAIM

The ornamental design for a chandelier as shown and described herein.

DESCRIPTION

FIG. 1 is a perspective view of the design, shown at a smaller scale;

FIG. 2 is a left view thereof;

FIG. 3 is a right view thereof;

FIG. 4 is a front view thereof;

FIG. 5 is a rear view thereof;

FIG. 6 is a top view thereof;

FIG. 7 is a bottom view thereof; and,

FIG. 8 is an enlarged view of the portion of the chandelier labeled "8" in FIG. 1.

The dash-dash broken lines showing portions of the chandelier form no part of the claimed design. The dash-dot broken lines illustrate the boundaries of the enlarged view, and form no part of the claimed design.

1 Claim, 8 Drawing Sheets
